CLAIM

The ornamental design for the interior vehicular rearview mirror display element, as shown and described.

DESCRIPTION

FIG. 1 is a front elevation view of a first embodiment of the interior vehicular rearview mirror display element showing our new design;

FIG. 2 is a rear elevation view of the mirror display element of FIG. 1;

FIG. 3 is a right end elevation view of FIG. 1, which is a mirror image of the left end elevation view;

FIG. 4 is a bottom plan view of FIG. 1;

FIG. 5 is a top plan view of FIG. 1;

FIG. 6 is a front elevation view of a second embodiment of the interior vehicular rearview mirror display element showing our new design;

FIG. 7 is a rear elevation view of the interior vehicular rearview mirror display element of FIG. 6;

FIG. 8 is a right end elevation view of FIG. 6, which is a mirror image of the left end view;

FIG. 9 is a top plan view of the display element of FIG. 6; and,

FIG. 10 is a bottom plan view of the display element of FIG. 6.
